TUBE ROLLING MILL

Jose Severin, Mulheim-Ruhr, Germany, assignor
to Deutsche Röhrenwerke Aktiengesellschaft,
Dusseldorf, Germany

Application November 9, 1934, Serial No. 752,281
In Germany November 25, 1933

5 Claims. (Cl. 80—13)

It is known to produce tubes from hollow billets by stretching the billets—chiefly in the axial direction—by means of rolls the axes of which are at an angle to the axis of the hollow billet and whose path of travel on the outer and inner faces of the hollow billet is of helical form; the rolls of the set of rolls around the periphery of the hollow billet are successively profiled in such manner that each succeeding roller further 5 treats the section of hollow billet already treated by the preceding roll. In these processes the outer rolls alone effect the shaping, while, in the interior of the block, a mandrel or smooth roll serves as a support, or alternatively rolls on the 10 inside take part in the shaping operation or perform it alone, while the outer rolls act as a smooth support.

The various kinds of shaping which are carried out by the profiled rolls differ in two principal respects. In one group the profiled rollers effect an operation known from the time of forging by the term "reduction by lowering" in which grooves are pressed into the billet by the first pair of rolls, so that a part of the blank is 15 reduced in diameter towards one end of the hollow billet; the part in question being widened smoothly towards the end by shoulders on the succeeding rolls which at the same time spread the metal while sometimes making deeper the 20 groove which has been formed in the metal by the first pair of rolls. In the second method the hollow billet is shaped by rolls profiled conically or smoothly or formed pointed in steps, in a manner corresponding to a drawing operation.

35 In the known processes the material being rolled is passed into the rolling mill on one side—the "entry" side—until it is gripped by the rolls and then driven through the rolling mill by them. The blank leaves the rolling mill on the 40 "discharge" side, and if it is to be passed through the rolling mill a second time, it must again be carried back to the entry side before it can again pass through the rolling mill. This conveying of the billet from the discharge side to the entry side is attended with difficulties and disadvantages. The rolling mills employed for carrying out the processes hereinbefore referred to are usually provided with a ring-shaped roll frame which carries the outer rolls that are driven by 45 spindles from a gear roll frame whose axis lies in alignment with the axis of the roll frame. These spindles hinder the blank from being returned to such a degree that the heated blank cools considerably, which is a distinct disadvantage in connection with the subsequent roll-

ing operation. Even when the rolls in the annular roll frame are not driven by spindles from the gear roll frame disposed on the same axis, but laterally, considerable difficulties are encountered in the returning of the rolled material; 5 these difficulties are caused by the operatives working on the rolling mill being obliged to reset the inside and outside rolls required for the next passage after each passage through the mill.

10 Methods of producing tubes are known in which after each passage of the material being rolled through the rolling mill itself there is a further passing through of the material in the opposite direction; thus for example a method 15 is known in which the rolls of an inclined rolling mill as ordinarily employed for piercing solid cylindrical billets are so provided that certain of the rolls cause the piercing while the material is passing through the rolling mill in one 20 direction while during the reverse movement, after the change of direction of the rolls, the remaining rolls cause the material which has been pierced while travelling in the original direction 25 to be stretched, whereby the walls of the tube produced are reduced in thickness and its length increased. Another known process, which makes use of the known conical roll discs for the intended shaping of the material being rolled effects 30 the to-and-fro movement of the rolled material 35 by using guides which are so provided that in one case the material being rolled is guided to the discs above their centre of rotation while in the other case the feed is effected below the centre of rotation of the discs which effect the 40 change of shape, and thus the direction of rolling is reversed without the reversal of the direction of rotation of the shape-changing discs.

These known methods for changing the direction of rolling cannot be employed for the 45 processes hereinbefore described in the second paragraph, because in these processes the returning of the material being rolled cannot be, made possible solely by reason of the fact that the rolling mill is run in the opposite direction. For 50 in these processes hereinbefore referred to the rolls are so profiled that the rolls which first come into action during the first passage of the material through the rolling mill grip the work by their shape-changing parts, the hollow blank 55 having its original thickness, while the shape-changing parts of the other rolls are unable to function correctly until the preceding rolls have already carried out part of the shape-changing operation. During the reverse movement of such 55

a rolling mill the shape-changing parts of the rolls that were last operating during the forward movement would be the first to grip the material. They would then be so heavily loaded that the 5 rolling mill would break or the billet would not be properly treated.

It is proposed according to the invention to roll the billet in both directions through rolls with two passes, which correspond to the sequence in the forward and rearward movements, the rolls whose first passes are operative in the forward movement being rocked after the forward movement, through such an angle that the second passes provided for the return movement come into the working position. The reduction 10 in the thickness of the material being rolled, which has been obtained as the result of the first passage through the rolls must be taken into account when determining the calibration of the 15 return movement. The two passes of the outer and inner rolls, or only of the outer rollers or only of the inner rolls can be set singly, it being possible for each of the rolls with two passes to be replaced by two rolls each adapted to be 20 profiled individually.

Apparatus according to the invention is diagrammatically illustrated by way of example in the accompanying drawings.

Figure 1 illustrates in longitudinal section a 30 roller mill with inner and outer rolls which are capable of being rocked out of alignment.

Figure 2 illustrates a similar rolling mill with inner rolls only which are capable of being thus moved.

Figure 3 illustrates a similar rolling mill with outer rolls only which are capable of being thus moved.

Figure 4 illustrates a complete tube rolling mill, with setting devices for rocking rolls B.

Figure 5 illustrates the mandrel head of a rolling mill provided with pairs of rolls each separately calibrated.

Each of the Figures 1 to 3 of the drawings illustrate a rolling mill provided with a circular 45 series of six pairs of rolls with the shaping parts operating on single helical lines when rotating in the clock-wise direction. Where it is advisable, for the sake of clearness, only to show in the drawings two pairs of rolls, the remaining rolls 50 are indicated in the following description by reference letters that do not appear on the drawings. Thus, outer rolls may be presumed to be numbered B₁, B₂, B₃, B₄, B₅ and B₆ and of these B₁ and B₄ are shown in the drawings and the inner rolls may similarly be considered to be numbered C₁, C₂, C₃, C₄, C₅, C₆ and of these C₁ and C₄ are shown in the drawings. The material A enters the first pass in the direction indicated by the full line arrow. The parts of the rolls which 60 operate on the entry side are numbered K₁, K₂, K₃, K₄, K₅ and K₆, of which K₁ and K₄ only are shown in the drawings, the pass K₁ functioning during the first passage of the material while the pass K₆ is operative last of all. In addition to 65 these passes each roller is provided with passes K'₁, K'₂, K'₃, K'₄, K'₅, and K'₆, K'₃ and K'₆ only being shown, K'₁ being formed by the rolls which form the pass K₆ in the direction of the original entry side and the pass K'₆ being formed by the 70 rolls which form the pass K₁ in the direction of the original entry side. If during the first passage the material being rolled is rotated from that position which may be termed the original entry side in the clockwise direction, it must in 75 the return movement be rotated from the original

entry side in the anti-clockwise direction, that is to say the material rotates in one direction in relation to the direction of passage of the tube through the mill. The direction of the return movement is indicated by dot-and-dash arrows. 5

In order to bring into use the passes K₁, K₂, K₃, K₄, K₅, K₆ or K'₁, K'₂, K'₃, K'₄, K'₅, K'₆ in the requisite manner and at the right time for the shaping operation the working rolls are provided to be capable of rocking that is to say the outer and inner rolls in Figure 1 only the inner rolls in Figure 2, and only the outer rolls in Figure 3. The rocking angle here corresponds to the depth of the depression. The pivotal points about which the rolls are rocked in the examples illustrated in Figures 1 to 3 are outside the rolls on the original entry side. They may, however, be otherwise selected, that is to say they may be inside the rolls themselves or at any other position according to the change of shape desired or 10 type of rolling mill employed. An example of this is illustrated in Figure 4.

In the constructions shown in Figures 2 and 3, in which only the inner or the outer rolls are rocked, the material being rolled moves the first 15 time it passes through—that is in the direction indicated by the full line arrow as in the example according to Figure 1 freely through the second pass without contacting with it. In the return movement of the material from the original discharge side in the direction indicated by the 20 arrow in dot-and-dash lines, the passes K₁ etc. formed by the rolls and their non-rocking counter rolls become operative after the rocking of the inner or outer rolls, by reason of the fact 25 that the rolls to be rocked are rocked not only to the extent indicated in Figure 1 but beyond this to such a degree that an increase or reduction is obtained in the diameter of the material by reason of the coning or entry of the inner and outer 30 rolls, as will be seen from the dot-and-dash lines 35 at F. Figure 2 illustrates a different roll pass at F from that shown in Figures 1 and 3.

The inner rolls are secured to the mandrel E in known manner by means of a roll head D. 45 As will be seen from Figure 4, the outer rolls B are mounted to rock in bearings H and in similar manner the inner rolls C are mounted in bearings J. The bearings for the inner rolls are capable of rocking by reason of their spherical 50 supporting base. The rocking movement as such can be obtained by a very large number of known machine elements.

Figure 5 illustrates a modified construction of the roll head D which is provided with a support 55 for the inner rolls C at the middle position, each of the inner rolls being divided into two rollers each having a separate pass. This arrangement has the advantage that rolls or roll spindles of small diameter may be employed just as might 60 be possible with undivided rolls on account of their length.

I claim:

1. A rolling mill for producing tubes from hollow billets by stretching, particularly in the axial direction, and comprising several sets of inner and outer rolls, the inner and outer units of which have their axes lying inclined to the path of travel of the hollow billet and are adapted to operate respectively upon the outer surface and the inner 70 surface of the hollow billet by grooving the material on helical lines and widening the groove, the rolls of the several sets of rolls which successively operate upon the billet being formed with passes related in such manner that every succeeding roll 75

set acts upon the part of the hollow billet which has already been acted upon by the preceding roll set, and means whereby the mill is adapted for rolling the hollow billet in both directions of travel through it, the said means consisting of passes provided upon the units of the several sets of rolls, certain of which passes are effective in one direction of travel of the hollow billet and certain of which passes are effective in the reverse direction of travel of the hollow billet, the passes for the reverse direction of travel being formed and positioned to continue the working of the billet carried out by the passes that are operative in the forward direction of travel of the billet and the rolls of each set of rolls being rotated in the reverse direction of rotation for the return direction of travel of the billet.

2. A rolling mill according to claim 1, having, included in the sets of rolls, rolls having passes which are operative respectively in the two directions of travel of the hollow billet and means whereby the axes of the rolls may be rocked to bring the pass required into operative position.

3. A rolling mill according to claim 1, wherein

sets of rolls include sets of which one roll is of fixed position and is of a form such that the required pass comes into operation according to the direction of travel of the hollow billet, and a second roll is adapted to be adjusted to render the two passes of the said rolls alternatively operative, the said rolls being provided with means for effecting the required adjustment.

4. A rolling mill according to claim 1, having, included in the sets of rolls a set of rolls which are operative for the one direction of travel of the hollow billet and other sets of rolls which are operative for the return direction of travel of the hollow billet.

5. A rolling mill according to claim 1, wherein the sets of rolls are provided to include sets of rolls of which one roll is formed with passes which are alternatively operative according to the direction of travel of the hollow billet and other rolls which are alternatively operative according to the direction of travel of the hollow billet co-operate respectively with the passes of the first roll.

JOSE SEVERIN.
